JET ENGINE VALVE CONSTRUCTION

Wesley Tracy Knight, Ogden, Utah

Application November 12, 1948, Serial No. 59,518

10 Claims. (Cl. 60—35.6)

1

This invention comprises novel and useful improvements in a jet engine valve construction and more generally pertains to a valve construction for supplying and exhausting combustion constituents to and from a combustion chamber, wherein the valve mechanism is automatically operable in response to predetermined change within the combustion chamber.

The primary object of this invention is to provide a valve construction for combustion chambers which will be automatically operable in response to pressure variations of a predetermined magnitude within said chamber, and which shall be of a simple dependable construction.

An important feature of this invention resides in the provision of a combustion chamber for jet engines and the like having an air and fuel inlet at its forward end and an exhaust discharge passage for a propulsion jet or the like at its rear end, together with an inlet and exhaust valve for controlling the inlet and exhaust passages, and wherein the valves are interconnected for automatic operation in response to predetermined pressure variations within the combustion chamber.

A still further feature of the invention resides in the provision of a cylindrical combustion chamber having oppositely disposed inlet and exhaust ports having valve seats, together with a rigidly connected exhaust valve for controlling the exhaust port and a piston disposed at the inlet port for operating the exhaust valve, and wherein the inlet valve port is formed in the piston and the inlet valve is slidably carried by said piston.

These, together with various ancillary features and objects of the invention which will later become apparent as the following description proceeds, are attained by this device, a preferred embodiment of which has been illustrated by way of example only in the accompanying drawings, wherein:

Figure 1 is a side elevational view, the combustion chamber being shown in central longitudinal sectional view, of a preferred embodiment of the invention;

Figure 2 is an end elevational view of the rear end of the device;

Figure 3 is an enlarged vertical longitudinal sectional view through the combustion chamber portion of the device, parts being broken away, and particularly showing the construction of the inlet and exhaust valve and associating mechanisms;

2

Figure 4 is a vertical transverse sectional detail view taken substantially by the plane of the section line 4—4 of Figure 3; and,

Figure 5 is an end elevational view taken from the right of Figure 3.

The present invention relates to a valving mechanism for a combustion chamber wherein a continuous stream of air at a more or less constant velocity is available for introduction by a ram effect into the front or inlet end of the combustion chamber, together with means for supplying fuel to form a combustible mixture within the chamber, and accompanied by valving mechanism for retaining the combustible mixture within the chamber while the same is exploded, and is further characterized by a differential pressure area construction for opening the exhaust valve after the combustion pressure has attained a predetermined value, to prevent the further ingress of a combustible mixture while the exhaust constituents are being discharged from the chamber. The ignition system which is particularly adapted for a combustion chamber of this character is fully described and set forth in my co-pending application Ser. No. 59,517, filed November 12, 1948, for Ignition System for Jet Engine.

It is to be understood that the combustion chamber and valve construction set forth hereinafter is particularly adapted for use with jet engines, for rocket propulsion and as an auxiliary impulse device which may be employed in various other environments such as upon the edge of helicopter blades or the like for assisting in imparting or in constituting the entire propulsive thrust thereto. The invention is particularly characterized by its ability to produce a substantially continuous stream of exhaust products of pulsating or varying pressure from a substantially constant pressure supply of air and fuel constituents, and whereby the valving action is obtained and timed solely by the pulsations of combustion pressure within the combustion chamber.

Referring now more specifically to the accompanying drawings, wherein like numerals designate similar parts throughout the various views, it will be seen that the numeral 10 designates generally a hollow body of any suitable character and which is preferably provided with a cylindrical bore 12 which opens at the forward end thereof, and which serves to provide a combustion chamber 14. At its closed rear end, the body 10 is provided with axially disposed exhaust port 16 having an exhaust valve seat 18 therein, and

a longitudinally extending exhaust discharge passage 20 communicates with the port 16 and hence with the combustion chamber 14, and its rearmost end is provided with an orifice 22 constituting a discharge jet for exhaust products produced by the combustion chamber of the device.

Disposed axially of the rear wall of the body 10 is a guide passage or bore 24 for the reception of a guide spindle 26 formed on the rear end of a valve 28 which may be of the well known poppet valve type, and which valve is thus guided and adapted to seat upon the valve seat 18 for controlling the flow and discharge of exhaust products from the combustion chamber 14 and through the exhaust discharge passage 20.

At its open forward or inlet end, the body 10 is provided with an externally threaded portion 30 for the reception of a retaining gland 32, having an air inlet opening 34 therein, which gland serves to retain a Venturi sleeve 36 within the bore 12.

Extending through the Venturi sleeve 36 into the throat of the venturi 38, is a fuel supply nozzle 40 by means of which liquid or other fuel is fed into the air stream flowing through the venturi, this fuel being supplied from any suitable source not shown, to thus provide and mix the elements of a combustible mixture which is discharged by the venturi into the combustion chamber 14 as set forth hereinafter.

A piston member 42 in the form of a disc or the like is slidably received in the bore 12 and has a sealing engagement with the walls of said bore as by means of one or more packing rings 44, this piston 42 having a bore 46 forming a continuation of the Venturi throat 38. This bore 46 at its inner end opens into a valve seat 48 which is adapted to be selectively controlled by the inlet poppet valve 50 as set forth herein-after.

An axially disposed stem 52 is integrally attached to or else otherwise rigidly secured to the exhaust valve 28 on the opposite side from the guide spindle 26 thereof, and at its forward end is provided with a diametrically disposed bore or bridge 54 which at its inner end is removably attached to the rearward end of the piston 42 as by a stepped or shouldered joint 56 and through the agency of fastening bolts 58. An axial guide bore 60 opens from the forward end of the stem 52 for receiving a guide spindle 62 integrally and axially extending from the inlet valve 50, and by means of which the latter is journaled in the stem 52 and guided for movement relative to the valve seat 48. The bore 60 is provided with a suitable vent opening 64 to prevent a dashpot or cushioning action within the bore against the end of the spindle 62, whereby the latter may be freely moved within the bore during its operation.

At its other side, the valve 50 is provided with an axial extension 66 which serves as an anchor for a tension spring 68 whose other end is secured to a hooked portion 70 of a support bracket 72 suitably carried by the Venturi bore 46 of the piston 42, whereby the disc valve 50 is tensioned into seating engagement with its inlet valve seat 48.

Preferably, the tension of the spring 68 is such that the valve 50 will be normally retained upon its seat until the pressure produced upon the valve by the ram effect of air flowing into the venturi 38 by reason of the forward motion of the body 10 through the atmosphere, would serve

to unseat the valve and permit the air to pass through the valve seat 48 drawing in with it fuel from the nozzle 40, to thus introduce a combustible mixture within the chamber 14.

It should be here noted that when the valve 50 is closed, the valve 50 together with the member 42 constitutes a piston whose area exposed to the pressure within the combustion chamber 14 is considerably greater than the area of the disc valve 28, so that when an explosion has occurred within the chamber 14, the piston 42 together with the valve stem 52 and the valve 28 will be moved towards the left and to the position shown in the Figure 3, thereby opening the exhaust valve and permitting the combustion products to discharge through the conduit 20 and orifice 22.

As shown in Figure 1, the body 10 is provided with a suitable drain cock 74 by means of which any condensate may be drained from the combustion chamber 14 and further the gaseous contents of the same may be exhausted to prepare the combustion chamber for its intended operation.

It will be here noted that this invention contemplates the arrangement and provision of a uniflow combustion chamber, whereby the gaseous constituents of the combustible mixture and the resulting combustion products of the same pass through the device without a change in their direction of travel, thereby increasing the rate of flow, and the ease of charging and exhausting the combustion chamber.

Various means may be provided with the valving arrangement for securing the ignition within the chamber in a properly timed relation to the position of the valves. However, it is preferred to utilize the ignition system set forth in my above identified co-pending application. Briefly, this ignition system, as illustrated in Figure 1, consists of the following element.

A spark plug, glow plug or other igniting device indicated at 76 extends through the walls of the body 10 to the combustion chamber 14 at any suitable point such as intermediate the ends thereof, and is connected with an ignition coil 78 in the customary manner, this coil being of any conventional design. An electric circuit associated with this coil, for controlling the primary circuit thereof by means of a braker arm 80 which is operated by a trip member 82 pivotally journaled as at 84 to a bracket 86 carried by the rearward end and outer surface of the body 10. A suitable battery 88 is connected with the braker and ignition coil whereby actuation of the braker arm 80 by means of rocking movement of the trip lever 82 will serve to make and brake the primer of the ignition coil and thereby induce a high tension current at the igniting device 76.

The trip lever 82 is journaled for movement in a vertical plane through the body 10, and its rear end is provided with a plate 90 which is positioned in the line of passage of the exhaust products from the exhaust jet or orifice 22. The plate 90 is preferably sufficiently weighted so that it will normally assume the position shown in Figure 1. However, when the velocity of the exhaust products from the orifice 22 reach their predetermined value, whereby predetermined force or pressure is applied against the plate 90, the trip lever 82 is caused to pivot upwardly about its fulcrum end 84, and thereby permit the braker arm 80 to establish its contact in the primary circuit of this ignition coil. When this occurs

fers, an ignition impulse is applied to the igniter 76, whereby the next ensuing combustible charge within the combustion chamber is again ignited. When the pressure from the orifice 22 has dropped to a predetermined value, the weight of the plate 98 again causes the trip lever 82 to pivot downwardly to the position shown in Figure 1 and the device is ready for its next operation.

Obviously, the inertia and mass of the lever 82 and plate 98 may be so chosen and selected that the igniter will be operated in properly timed synchronization with the attainment of an explosive charge within the combustion chamber.

Referring now to Figure 3 it will be seen that after the exhaust of a previous explosion has occurred, the force exerted by the incoming charge of air through the venturi 38 will move the piston 42 with the valve 50 being closed by the tension of the spring 68, and thereby through the stem 52 will likewise move the exhaust valve 28 towards the right whereby the exhaust valve will be seated on its valve seat 18, to close the discharge end of the combustion chamber. Further pressure of the incoming air and fuel will now open the inlet valve 50, and charge the combustion chamber 14. When the pressure therein has been substantially equalized with the pressure of the incoming charge through the venturi 38, the spring 68 will then enclose the inlet valve 50 whereby the interior of the combustion chamber will be sealed, and ignition will be produced therein by the previously described ignition system. When the pressure of the combustion rises to a predetermined value, this pressure acting upon the differential areas of the piston 42 and the exhaust valve 28 will move the piston and exhaust valve assembly towards the left, until the piston seats against the end of the venturi 36, thereby withdrawing the exhaust valve from its seat.

When the pressure within the combustion chamber 14 has dropped to a predetermined value by reason of the escape of the combustion products through the passage 20 and orifice or jet 22, the constant pressure of the incoming charge will again move the piston assembly 42 and the rigidly attached exhaust valve 28 to the right, thereby closing the exhaust valve, and repeating the cycle of operation. Thus a series of sequential combustion charges are enclosed and fired within a combustion chamber for producing a pulsating exhaust pressure discharged through the passage 20 and the exhaust nozzle or jet 22.

It should be noted that the relatively constant pressure of the incoming air component of the combustible charge serves to inspire or draw in fuel from the fuel nozzle 40 and to mix this fuel to provide a combustible mixture during and prior to its introduction to the combustion chamber 14. It will be further noted that both the inlet and exhaust valves are provided with spin-dles which are axially guided to insure even seating of the valves upon their valve seats, and that the inlet valve is opened and closed substantially by the difference in pressure of the incoming charge with the pressure prevailing within the combustion chamber, while the exhaust valve is closed by the pressure of the incoming charge against the piston 42, and opened by the pressure difference arising from the differences in area of the piston and the exhaust valve.

From the foregoing, it is thought that the construction and operation of the device will be

readily understood and further explanation of the same is believed to be unnecessary. However, it is evident that the principles of the invention may be realized and carried out by a great variety of structures and may be utilized in various environments, and accordingly it is not desired to limit the invention to the exact construction shown and described, but all suitable modifications and equivalents may be resorted to, falling within the scope of the appended claims.

Having thus disclosed and described the invention, what is claimed as new is as follows:

1. A jet engine including a combustion chamber having a combustible mixture inlet port and a combustion products outlet port at its opposite ends, a valve seat for each port and a valve for each seat, each valve being yieldingly urged upon its seat by the fluid pressure within the combustion chamber, means responsive to the pressure variations within said chamber for operating said valves, said last means including a piston slideable in said combustion chamber and connected to the outlet valve, the piston being of greater area than said outlet valve for forcing the latter from its seat when the combustion chamber pressure exceeds a predetermined value.

2. A valve construction for a uniflow combustion chamber having an inlet passage, an inlet port communicating with said inlet passage and having an inlet valve seat, an outlet passage having an outlet port, valves controlling each of said ports, means for supplying a combustible mixture to said inlet port, means responsive to predetermined pressure variations in said chamber for operating said valves, said last means including a piston slideable in said combustion chamber and connected to the outlet valve, the piston being of greater area than said outlet valve for forcing the latter from its seat when the combustion chamber pressure exceeds a predetermined value.

3. A jet engine including a combustion chamber having a combustible mixture inlet port and a combustion products outlet port at its opposite ends, a valve seat for each port and a valve for each seat, each valve being yieldingly urged upon its seat by the fluid pressure within the combustion chamber, means responsive to the pressure variations within said chamber for operating said valves, said last means including a piston slideable in said combustion chamber and connected to the outlet valve, the piston being of greater area than said outlet valve for forcing the latter from its seat when the combustion chamber pressure exceeds a predetermined value, said piston including said inlet valve seat and said inlet valve.

4. A valve construction for a uniflow combustion chamber having an inlet passage, an inlet port communicating with said inlet passage and having an inlet valve seat, an outlet passage having an outlet port, valves controlling each of said ports, means for supplying a combustible mixture to said inlet port, means responsive to predetermined pressure variations in said chamber for operating said valves, said last means including a piston slideable in said combustion chamber and connected to the outlet valve, the piston being of greater area than said outlet valve for forcing the latter from its seat when the combustion chamber pressure exceeds a predetermined value, said piston including said inlet valve seat and said inlet valve.

5. A jet engine including a combustion cham-

ber having a combustible mixture inlet port and a combustion products outlet port at its opposite ends, a valve seat for each port and a valve for each seat, each valve being yieldingly urged upon its seat by the fluid pressure within the combustion chamber, means responsive to the pressure variations within said chamber for operating said valves, said last means including a piston slidable in said combustion chamber and connected to the outlet valve, the piston being of greater area than said outlet valve for forcing the latter from its seat when the combustion chamber pressure exceeds a predetermined value, said piston including said inlet valve seat and said inlet valve, said outlet valve having a stem extending longitudinally of said chamber, said stem being secured to said piston, a guide bore in said stem, said inlet valve having a spindle slidably guided in said bore and resilient means urging said inlet valve towards its seat.

6. A valve construction for a uniflow combustion chamber having an inlet passage, an inlet port communicating with said inlet passage and having an inlet valve seat, an outlet passage having an outlet port, valves controlling each of said ports, means for supplying a combustible mixture to said inlet port, means responsive to predetermined pressure variations in said chamber for operating said valves, said last means including a piston slidable in said combustion chamber and connected to the outlet valve, the piston being of greater area than said outlet valve for forcing the latter from its seat when the combustion chamber pressure exceeds a predetermined value, said piston including said inlet valve seat and said inlet valve, said outlet valve having a stem extending longitudinally of said chamber, said stem being secured to said piston, a guide bore in said stem, said inlet valve having a spindle slidably guided in said bore and resilient means urging said inlet valve towards its seat.

7. A valve construction for a uniflow combustion chamber having an inlet passage, an inlet port communicating with said inlet passage and having an inlet valve seat, an outlet passage having an outlet port, valves controlling each of said ports, means for supplying a combustible mixture to said inlet port, means responsive to predetermined pressure variations in said chamber for operating said valves, said last means including a piston slidable in said combustion chamber and connected to the outlet valve, the piston being of greater area than said outlet valve for forcing the latter from its seat when the combustion chamber pressure exceeds a predetermined value, said piston including said inlet valve seat and said inlet valve, said outlet valve having a spindle on the opposite side from said stem, a guide for slidably receiving said outlet valve spindle.

8. A valve construction for a uniflow combustion chamber having an inlet passage, an inlet port communicating with said inlet passage and having an inlet valve seat, an outlet passage having an outlet port, valves controlling each of said

10

ports, means for supplying a combustible mixture to said inlet port, means responsive to predetermined pressure variations in said chamber for operating said valves, said last means including a piston slidable in said combustion chamber and connected to the outlet valve, the piston being of greater area than said outlet valve for forcing the latter from its seat when the combustion chamber pressure exceeds a predetermined value, said piston including said inlet valve seat and said inlet valve, said outlet valve having a stem extending longitudinally of said chamber, said stem being secured to said piston, a guide bore in said stem, said inlet valve having a spindle slidably guided in said bore and resilient means urging said inlet valve towards its seat, said outlet valve having a spindle on the opposite side from said stem, a guide for slidably receiving said outlet valve spindle.

9. In a jet engine a body having a cylindrical combustion chamber therein, an air intake venturi at the forward end of said body and an exhaust orifice in the rear end of said body each opening with said chamber, means for supplying fuel to said venturi to form a combustible mixture, a piston slidable in said chamber and engageable against said venturi, an exhaust valve controlling flow through said orifice and rigidly connected to said piston for movement therewith, and inlet port extending through said piston, an inlet valve slidably carried by said piston for controlling said inlet port, said inlet valve being spring closed and opening by flow through said venturi, said piston being of greater area than said exhaust valve whereby the latter will be opened by said piston when the pressure within said chamber exceeds a predetermined value.

10. A jet engine including a combustion chamber having a combustible mixture inlet port and a combustion products outlet port at its opposite ends, a valve seat for each port and a valve for each seat, means responsive to the pressure variations in said chamber for operating said valves, said last means including a piston slidable in said chamber and connected to said exhaust valve, the piston being actuated by a predetermined fluid pressure in said combustion chamber to force the outlet valve from its seat, said piston including said inlet valve seat and said inlet valve.
